UNITED STATES PATENT OFFICE.

CHARLES RICE WARNER, OF PORTLAND, OREGON.

WELSBACH-MANTLE HOLDER.

No. 873,690.

Specification of Letters Patent.

Patented Dec. 10, 1907.

Application filed November 30, 1906. Serial No. 345,850.

To all whom it may concern:

Be it known that I, CHARLES RICE WARNER, a citizen of the United States, and a resident of Portland, in the county of Multnomah and State of Oregon, have invented a new and useful Improvement in Welsbach-Mantle Holders, of which the following is a specification, reference being had to the accompanying drawings as constituting a part thereof.

This invention relates to the perforated burner-tips of gas arc-lamps and has for its object to facilitate the cleaning of such burner-tips, to facilitate the removal of the mantle supporter or holder for the purpose of such cleaning, or trimming, and to enable the mantle-holder to be shortened to lower the mantle, as may be desirable when the bottom of the mantle only has been injured or broken, and the mantle may still be used for a time by merely lowering the same somewhat; and by the result so obtained, to prolong the life of the parts and to correspondingly lessen the cost of maintenance of the lamp.

In the present arrangement of the devices concerned, the effective and rapid cleaning of the burner-tip is frequently impossible, after the burner has been used for any length of time; and the same is true concerning the removal and shortening of the mantle-holder; because these parts of the burner-tip are exposed to the flame and soon become corroded by the products of combustion and the high temperature. When this has occurred the mantle-holder has usually become stuck fast in its socket, so that it cannot be removed, and this condition necessitates the throwing away of a burner-tip and the substitution therefor of a new one, when the former would otherwise have been continued in service for a considerably longer time. The inability to remove the mantle-holder also greatly increases the work of cleaning the perforations in the burner-tip, making it necessary to use a pricking point, while if the mantle-holder could be removed a stiff brush could be effectively used; and, furthermore, the removal of the burner-tip and replacing thereof by a new one is a time consuming, and frequently unsuccessful work, because of the burner-cap having also become corroded and weakened in service whereas if the mantle-holder could be removed the required work of cleaning and repair could be quickly and successfully done,

for the weakened parts would only receive such handling as they could stand, notwithstanding their more or less fragile condition. To this end I combine my mantle supporter or holder with a shield, so arranged as to protect the central part of the burner-tip and the socket there provided in which the lower end of the mantle-holder is stuck, against the heat of the flame, and also against the deposits of the solid, corroding products of combustion.

The arrangement of my device is shown in the drawings, in which,

Figure 1 is an elevation of a burner of the type referred to, also showing the mantle-holder in place and my invention applied thereto; Fig. 2 is an enlarged sectional detail of the parts comprised within the upper portion of the preceding figure; Fig. 3 is a plan of the burner-tip and of my shield in place, the parts being drawn on a scale corresponding with that of Fig. 2; and Figs. 4, 5, 6, & 7 are details of modifications of construction.

Referring now to the reference letters: my invention is only concerned with the perforated burner-tip and parts supported thereby. The other parts of the burner *a*, are of the usual construction; *i. e.* *b* represents the usual tapered expansion-tube on which is mounted, in the usual manner, a Bunsen head-shell *c*, and on the latter is mounted a Bunsen cap *d*. On the rim of the head-shell *c* rests the perforated burner-tip *e*, and the latter is held in place as usual by the cap *d*, the upper end of which is made with a slight flange or crimp, as usual, for that purpose.

The burner-tip is made with an integral socket *f*, in which is inserted the lower end of the mantle-holder *g*, from the upper end of which the mantle *h* is supported. It is thus apparent that, in the former assemblage of the parts last referred to, after the mantle-holder *g* has been inserted in the socket *f*, quite a crevice would be left uncovered in the socket in which solid particles of the products of combustion could collect; and, furthermore, experience has shown that the central part *i* of the burner-tip soon becomes corroded to such extent as to immovably bind the mantle-holder *g* in place. Consequently when it was necessary to clean the perforations in the burner-tip, a brush could not be used, but only a pricking point. Furthermore under the same conditions, in case

the lower part of the mantle had been burned away or otherwise damaged there was no way of repairing the parts except by the removal of the cap *d*, and the substitution of a new burner-tip *e*, and a mantle-holder *g*, the lower end of which is broken away sufficiently to allow the mantle to be lowered as required. These manipulations of course required considerable time; and moreover the crimped edge of the cap *d* is also subjected to the described corroding action and becomes weak; and the same is true with respect to the burner-tip, so that if these parts are unnecessarily handled it is found that they are broken and cannot be replaced, requiring the substitution of new parts; whereas if they had been left alone they could have been continued in service for still a considerable time. To remedy the defects referred to I provide a shield *j*, consisting of a circular-piece of metal or other suitable material, having a central perforation and so formed as to have a convexed under side *k*. The central perforation of the shield is made of size to just snugly receive the mantle-holder *g*.

The parts are assembled as shown in Fig. 2, and it will be found that the shield *j* is an effectual guard for the socket *f* against the corrosive action caused by the products of combustion and high temperatures, and that the mantle-holder *g* can be removed at will at any time; and should it be desired to shorten the mantle-holder for the purpose of lowering the mantle, this may be readily done, notwithstanding that the shield has become bound to the mantle-holder, for the lower end of the latter is to be broken away anyway, and the shield only costing a trifle, the mantle-holder may be broken away so as to readily remove the shield and then a new shield placed in such position on the mantle-holder as to lower the latter as desired. The upper surface of the shield *j* receives all deposits of the products of combustion, and by reason of the same being so formed as to have a convexed under side, providing there a small air space, the shield constitutes an effective barrier against the heat reaching the central part of the burner-tip. The shield also serves to hold the mantle-holder *g*

in its proper vertical position, and avoids the leaning of the mantle to either side.

The possible modifications in the construction of my shield *j* are apparent when examining the shields *j'*, *j''*, *j'''*, shown in Figs. 4, 5, and 6, and such modifications make it clear that the form of the shield is subject to variation, and that the exact form thereof is immaterial as far as accomplishing the result in mind is concerned. I prefer the type of shield shown in Fig. 4 with respect to the upwardly projecting rim-flange *l*, formed around the central hole, which flange provides a good hold for the mantle-holder *g*. The flange *l* may be easily formed in the operation of cutting out the central hole in the shield. But I do not confine myself to any particular form of shield.

I claim:

1. In a burner of the type described, the combination with a perforated burner tip provided with a depending hollow extension to form a socket, a mantle holder fitting loosely in the socket and extending upwardly therefrom, a shield of thin light material mounted on the mantle support above the perforated burner tip and having its central portion slightly spaced therefrom and its outer edge resting snugly on and supported by the burner tip said shield serving to protect the central portion of the burner tip and its socket against high temperature and corrosion.

2. In a burner of the type described, the combination with a perforated burner tip provided with a depending hollow extension to form a socket, a mantle holder fitting loosely in the socket, a convex shield of thin light material mounted on the mantle support above the perforated burner, the outer rim of the thin convex shield resting on and supported by the burner tip thereby providing an air space between the central part of the burner tip and the underside of the shield, to protect the central part of the burner tip and its depending socket against high temperature and corrosion.

CHARLES RICE WARNER.
